CHINA CABINET WITH CARVED DOORS OR THE LIKE

Joseph E. Adkinson, 3807 Leland St.,
Chevy Chase, Md. 20015

Filed Feb. 4, 1972, Ser. No. 223,822

Term of patent 14 years

Int. Cl. D6—04

U.S. Cl. D6—154

FIG. 1

FIG. 2

FIG. 3

FIG. 1 is a view in front elevation of a china cabinet with carved doors showing my design.

FIG. 2 is a view in side elevation of the cabinet of FIG. 1.

FIG. 3 is a bottom view of the cabinet of FIG. 1.

The back of the cabinet is conventionally flat and the side not shown is identical to the side shown in FIG. 2.

I claim:

The ornamental design for a china cabinet with carved doors or the like, substantially as shown and described.
